T. MURGATROYD, Jr.

Carriage-Spring.

No. 12,764.

Patented Apr. 24, 1855.

UNITED STATES PATENT OFFICE.

THOMAS MURGATROYD, JR., OF SMITHVILLE, CANADA WEST.

CARRIAGE-SPRING.

Specification of Letters Patent No. 12,764, dated April 24, 1855.

To all whom it may concern:

Be it known that I, THOMAS MURGATROYD, Jr., of Smithville, in the district of Niagara and Province of Canada West, have invented a new and useful Improvement in Carriage-Springs; and I do hereby declare that the following is a full, clear, and exact description of the same, reference being had to the annexed drawings, making a part of this specification, in which—

Figures 1 and 2 are front views of my improvement. Fig. 3, is a longitudinal vertical section of ditto, the plane of section being through the center. Fig. 4, is an inverted plan of ditto.

Similar letters of reference indicate corresponding parts in the several figures.

This invention relates to a new and useful improvement in carriage springs, and consists in the peculiar arrangement of the springs and the manner in which they are connected or applied to the vehicle.

To enable others skilled in the art to fully understand and construct my invention, I will proceed to describe it.

A, A', represent the springs, two at the front part of the vehicle and two at the back part. These springs are of curved or bow form, similar to the upper half of the ordinary elliptic spring. The springs are placed one over the other at the front and back of the vehicle as shown in Figs. 1 and 2, and the springs are of sufficient length to extend as far as the arms (a) of the axles B, of the wheels. The upper springs A, are connected at their ends by links (b) to the upper ends of rods (c) which are attached to the upper surfaces of the arms and the lower springs A', have their ends connected by links (d) to eyes (e) which project downward from the under surfaces of the arms, see Figs. 1 and 2. Between each pair of springs A, A', there is a stay or rod C, as shown in Figs. 1, 2 and 3. To the upper surfaces of the upper springs A, at about their centers the usual bolsters (f) are secured and upon which the body F, (the bottom of which is only shown) of the vehicle rests. Between the bolster and body of the vehicle at the front part of the vehicle a fifth wheel (g) is placed.

D, is a brace the ends of which are con-

nected to the front and back axles. The back part of the brace is forked, see Fig. 4, and the prongs (h) (h) are connected near the ends of the back axle but the front end of the brace is connected to the front axle by a bolt or pivot (i) shown in all the figures.

E, E', are braces which are connected to the lower springs A', and to the center of the body F, underneath by a pivot (j) as shown in Figs. 3 and 4. The front brace E, is allowed to move or turn slightly on the pivot (j).

By the above improvement the weight of the vehicle or rather the body and its load rests equally upon both springs A, A', as they are connected by the stays or rods C, C, and the thrust of the springs and the weight of the load bears upon the arms (c) of the axles B, no weight bearing upon the centers of the axles. All the strain that the axles are subjected to is lateral, caused by the thrust of the springs, the arms (c) sustaining the weight of the load.

I am enabled by the above improvement to use long springs extending the whole length of the axles and the springs are therefore sufficiently elastic to yield or give so that if either of the wheels is suddenly depressed or raised in passing over obstructions or into holes in the road the load and body of the vehicle will not be moved out of its proper position the springs yielding sufficiently to prevent this, see Fig. 2, in which one end of the springs and axle is raised. The springs also are prevented from being moved or wrenching forward or backward by the braces E, E', which also form a support to the body F, and the brace D, supports or keeps in proper position the axles B, B.

The above improvement can be made and applied to vehicles in about one third the time required for the manufacture of the ordinary springs and applying or attaching them to vehicles, one third less weight of metal is required and superior strength and durability is obtained, and the expense of construction is about one third less than if the ordinary carriage springs were applied.

Having thus described my invention, what

I claim as new and desire to secure by Letters Patent, is—

The employment or use of the springs A, A', attached to the arms (a) of the axles 5 B, B, by links b, d, the links (b) being above, and the links (d) below the arms of the axle, the two springs A, A', being connected by stays or rods C. The springs be-

ing also braced to prevent a forward and backward motion of the same and the axles 10 B, being supported or braced by the rod or brace D, as herein shown and described.

THOMAS MURGATROYD, JR.
